UNITED STATES PATENT OFFICE.

ANDREW ROBERT ROBERTSON, OF KINGSTON, GLASGOW, SCOTLAND.

CENTRIFUGAL MACHINE.

1,127,284.

Specification of Letters Patent. Patented Feb. 2, 1915.

Application filed May 8, 1914. Serial No. 887,867.

To all whom it may concern:

Be it known that I, ANDREW ROBERT ROBERTSON, a subject of the King of Great Britain and Ireland, and a resident of Kingston, in the city and county of Glasgow, Scotland, have invented certain new and useful Improvements in Centrifugal Machines, of which the following is the specification.

10 This invention relates to that class of centrifugal machine used for treating sugar or granular material in which the discharge of the dried contents is assisted by a basket bottom sloping inwardly at an angle greater than the angle of repose of the material.

15 The invention has for its object to still further facilitate the discharge when the bottom is sloping.

According to the invention the shell of 20 the revolving basket is in the form of the frustum of a cone, smaller end upward, instead of, as usual, being cylindrical.

Baskets having conical shells are known, but the essence of the invention lies in the 25 combination of such a shell with a bottom part sloping at an angle greater than the angle of repose of the material being dried.

In the known construction in which the basket has cylindrical sides and a bottom 30 sloping at an angle greater than the angle of repose of the material being dried, though the material resting upon the sloping and inclined bottom is usually automatically discharged when the machine

35 stops, yet it is sometimes the case that the consistency of the material is such that there is sufficient adhesion of the material to the usual cylindrical sides of the basket to impede discharge. With the truncated conical shell however, the slightest downward movement of the lower portion of the material on the sloping bottom immediately frees the then unsupported remainder of the material from the sides of the basket, and gravity causes this portion of the material to at 45 once follow the portion leaving the sloping bottom. Discharge of the entire contents of the basket is thus insured.

An example of the improved construction 50 of centrifugal basket is shown in vertical section on an accompanying sheet of explanatory drawings.

As shown in this drawing, the basket is 55 of the type in which there is an annular discharge opening A, and the bottom B of the

basket slopes downward from the shell C at such an angle that the dried contents will not lie on it when the basket is at rest, but immediately fall by their own weight, and are discharged through the annular opening A. The shell C is also inclined, that is, it is in the form of the frustum of a cone, smaller end upward, the angle shown being about two degrees to the vertical. This insures that after the material resting upon the inclined bottom is discharged, the then unsupported remainder of the material opposite to and adhering to the shell C of the basket will be freed therefrom, and gravity will cause this portion of the material to at once follow the portion leaving the sloping bottom B.

It will be evident that the angle to which the shell of the basket is inclined to the vertical depends on the nature of the material to be treated. For high grade and readily drying sugars, for example, the angle shown in the drawing is sufficient, but for lower grade sugar, or other more viscous materials, the angle to the vertical should be increased by a few degrees.

The basket is charged while running, the material being fed on to a distributing plate D, secured on the carrying spindle E, and thrown against the shell C of the basket by centrifugal force.

What I claim is—

1. In a centrifugal machine, a basket, an annular discharge opening in the bottom thereof, a bottom at an angle greater than 90° the angle of repose of the material being dried, in combination with a shell for the basket in the form of a frustum of a cone, smaller end upward, as described.

2. In a centrifugal machine, a basket, an annular discharge opening in the bottom thereof, a bottom at an angle greater than the angle of repose of the material being dried, in combination with a shell for the basket in the form of a frustum of a cone, 100 smaller end upward, and the walls of the shell being inclined inwardly from the vertical to such extent that the material being dried ceases to adhere to the shell when unsupported from below by reason of the 105 downward movement of the material on the sloping bottom, as described.

3. In a centrifugal machine, a basket, an annular discharge opening in the bottom thereof, a bottom at an angle greater than 110

the angle of repose of the material being dried, in combination with a shell for the basket in the form of a frustum of a cone, smaller end upward, the angle to the vertical of the shell being substantially two degrees, as described.

In testimony whereof I have signed my

name to this specification, in the presence of two subscribing witnesses.

ANDREW ROBERT ROBERTSON.
